(57) **CLAIM**

The ornamental design for a toy rocket, as shown and described.

DESCRIPTION

FIG. 1 is a top perspective view of the toy rocket showing the present design.

FIG. 2 is a right side view thereof.

FIG. 3 is a left side view thereof.

FIG. 4 is a top view thereof.

FIG. 5 is a bottom view thereof.

FIG. 6 is a front view thereof; and,

FIG. 7 is a rear view thereof.

The broken lines shown in the figures are for the purpose of illustrating portions of the toy rocket and form no part of the claimed design.
